UNITED STATES PATENT OFFICE

HARLEY E. ANDERSON, OF KANSAS CITY, MISSOURI, ASSIGNOR TO GUSTIN-BACON MANUFACTURING CO., OF KANSAS CITY, MISSOURI, A CORPORATION OF MISSOURI

SLACK ADJUSTER

Application filed June 12, 1930. Serial No. 460,573.

My invention relates to that class of devices used in connection with air brakes on railroad cars.

My invention has for its object, to provide a device which will automatically and continuously take up the slack in the brake rods caused by the wearing of the brake shoes.

My invention has for its further object, to accomplish the above by shortening the top rod rather than by moving the brake cylinder levers.

Another object is, to construct the device so that the levers, actuated by the air brake cylinders, will be continuously held in right angled relation to the center line of the brake cylinder, as there will never be any appreciable slack, and in this way will materially decrease the liability of the brake rigging fouling, either on the car frame or the car wheels, which results when there is considerable slack.

A concrete embodiment of my invention is illustrated in the accompanying drawings, which are to be considered as a part of this specification, in which—

Fig. 1 is a phantom top plan view through the floor of a freight car, showing my improved device attached to the brake rigging;

Fig. 2 is an enlarged detail view, partly in section, showing the brakes in released position;

Fig. 3 is a similar view, showing the position of the device when the brakes are set, and with no wear on the brake shoes;

Fig. 4 is a similar view of the device, showing its position when the brakes are set, with the top rod taken up or shortened, to compensate for the wear on the brake shoes which have partially worn off;

Fig. 5 is an enlarged detail view, in side elevation;

Fig. 6 is a similar view, in plan; and

Fig. 7 is a sectional view, taken on line 7—7 in Fig. 5.

Similar reference numerals refer to similar parts throughout the entire description.

In the drawings, the floor 1 of the car is shown in dotted lines, as obviously it forms no part of my invention. The wheels 2,

brake shoes 3, dead levers 4 of each truck, lower rods 5 which connect the dead levers 4 with floating truck levers 6, top rods 7 and 8 connected to the floating cylinder lever 9 and dead lever 10, the cylinder lever rod 11 and the brake push rod 14, are of the usual standard type employed in railroad cars as now constructed. The brake push rod 14 is connected to the air brake piston (not shown), slidably mounted in the air cylinder 15, the latter and its air reservoir 16 being supported below the floor 1 of the car. In view of the fact that the construction of my device for the top rods 7 and 8 is just alike, I shall only describe a single construction, it being understood there is a similar device mounted on the other top rod.

The top rod 7 is provided with an upset portion 17, which is provided preferably with a thread 18 of coarse pitch, which is of sufficient length to take up the wear of the brake shoes 3. This rod 7 extends into a member 19, which for convenience I term a jaw casting, though obviously it may be forged or formed in any other desired manner.

The end 20 of the casting 19 is secured to the floating lever 9, by means of a pin 21. This casting 19 is formed with a yoke 22, in which is mounted a ratchet wheel nut 23. The wheel portion of this nut 23 has a plurality of ratchet teeth 24 cut on its periphery, and has internal threads which fit the threads 18 on the upset portion 17 of the top rod 7. The nut 23 has a laterally-extending hub 25 on one side, the exterior of which is knurled to provide for its convenient manipulation.

In order to protect the threads 18 from injury, a tube 26, preferably formed of steel, is mounted in the end of the jaw casting 19, and extends outwardly far enough to cover the threads 18, thus effectually preventing their being injured. On one side of the casting 19, adjacent the yoke 22, is a laterally-extending stud 27. Rotatably mounted upon this stud 27 is a trigger lever, which, as clearly seen in the detail views, consists of a cylindrical portion 28, and a bell crank portion having arms 29 and 30, the latter having a

tooth-engaging portion which meshes with the ratchet teeth 24 on the ratchet wheel 23.

Within the cylindrical portion 28, I mount a coil spring 31, which is both a twist and compression spring, one end 31 of which is secured to a flat washer 33, which is fitted to the end 34 of the stud 27. This end 34 has a segment milled off, forming a flat side, so that the washer 33 cannot rotate thereon, a pin 35 serving to hold the washer 33 in place, and thus put the spring 31 under compression.

The other end 36 of the spring 31 is attached to the inner wall 37 of the cylindrical portion 28, and serves to hold the trigger in the position shown in full lines in Fig. 5.

I provide a permanent stop bracket 38, located on the car frame so that, under normal conditions, the arm 29 of the trigger does not touch it. When the brakes are in released position, the device is as shown in Fig. 2. When the brakes are set, as shown in Fig. 3, the top rod 7 is moved back, carrying with it the jaw casting 19. This brings the trigger arm 29 almost in contact with the permanent stop 38. If there is any wear, producing looseness of the top rod 7, the trigger arm 29 will strike the permanent stop 38. This will rotate the trigger on its stud 27, causing the tooth-engaging portion 30 to catch the next lower tooth on the ratchet wheel 23, when the spring 31 will cause the trigger lever 29 to return to its normal position after the release of the brakes. This revolves the nut 23 on the thread 18, and shortens the top rod 7. The spring 31 also yields by compression, permitting the needed up-and-down movement over the teeth 25 on the ratchet nut 23. Inasmuch as this occurs every time there is any wear, it follows I am able to keep the brake rigging normal at all times, regardless of the wear of the brake shoes 3, and hence I can maintain the floating and dead levers 9 and 10 at right angles to the center line of the air cylinder 15, which is the ideal operative position.

When the brake shoes 3 are so worn that they must be replaced, this is accomplished by pulling the trigger lever arm 29 around until it is free of the ratchet teeth 25, when the hub 26 can be turned by hand until the required slack is obtained.

Having described my invention, what I regard as new, and desire to obtain by Letters Patent of the United States, is:

1. In a device of the character described, the combination, with a brake rigging having cylinder lever and top rods, of a threaded portion on the top rods, a member, pivotally secured to the cylinder lever, having a longitudinal opening into which the threaded portion on the top rod extends, a ratchet nut rotatably mounted in said member, which holds it from longitudinal movement, ratchet teeth cut on a portion of the periphery of said nut, a laterally extending stud on said

member, a rotatable trigger lever mounted on said stud, a hollow hub, on the trigger lever, spring means mounted in said hub which permit said hub to move longitudinally of said stud and which rotates said trigger lever when the brakes are released, arms on said hub, one of which engages the said ratchet teeth, and a permanent stop, against which the other arm of the trigger lever abuts when the brakes are set and the brake shoes are worn.

2. In a device of the character described, the combination, with a brake rigging having cylinder lever and top rods, of a threaded portion on said top rods, a jaw casting, a laterally extending stud on said casting, a trigger lever mounted thereon, a ratchet wheel nut mounted in said jaw casting and on said threaded portion of a top rod, a permanent stop, against which said trigger lever abuts when the brakes are set and the brake shoes are worn, a spring attached to said trigger lever which permits it to move longitudinally on said stud and which rotates said lever when the brakes are released.

3. In a device of the character described, the combination, with a brake rigging having cylinder lever and top rods, of a threaded portion on said top rods, a jaw casting, a laterally extending stud, a ratchet wheel nut mounted in said jaw casting and on said threaded portion of a top rod, means, actuated by the longitudinal movement of the top rod mounted on said stud, which rotates said nut if there is any slack in the brake rigging and a spring which permits said means to move longitudinally on said stud and which rotates said means thereon when the brakes are released.

4. In a device of the character described, the combination, with a brake rigging having cylinder lever and top rods, of a threaded portion on said top rods, a jaw casting, a laterally extending stud thereon, a ratchet wheel nut mounted in said jaw casting and on said threaded portion of a top rod, means, actuated by the longitudinal movement of the top rod mounted on said stud, which rotates said nut if there is any slack in the brake rigging, and spring means to permit said actuated means to move longitudinally on said stud and to return said actuated means to normal position after the brakes are released.

5. In a device of the character described, the combination, with a brake rigging having cylinder lever and top rods, of a threaded portion on said top rods, means to protect said threaded portion, a jaw casting, a laterally extending stud thereon, a ratchet wheel nut mounted in said jaw casting and on said threaded portion of a top rod, means, actuated by the longitudinal movement of the top rod, which rotates said nut if there is any slack in the brake rigging, and spring means mounted in said actuated means which per-

mits said actuating means to move longitudinally of said stud and to return said actuated means to normal position after the brakes are released.

6. In a device of the character described, the combination, with a brake rigging having cylinder lever and top rods, of a threaded portion on the top rods means to protect said threads, a member, pivotally secured to the cylinder lever, having a longitudinal opening into which the threaded portion on the top rod extends, a ratchet nut rotatably mounted in said member, which holds it from longitudinal movement, ratchet teeth cut on a portion of the periphery of said nut, a laterally extending stud on said member, a knurled portion on said nut, a rotatable trigger lever mounted on said stud, a hollow hub on the trigger lever, spring means mounted in said hub which permit said hub to move longitudinally of said stud and which rotates said trigger lever when the brakes are released, arms on said hub, one of which engages the said ratchet teeth, and a permanent stop, against which the other arm of the trigger lever abuts when the brakes are set and the brake shoes are worn.

7. In a device of the character described, the combination, with a brake rigging having cylinder lever and top rods, of a threaded portion on said rods, a jaw casting, a laterally-extending stud on said casting, a trigger lever mounted thereon, a ratchet wheel nut mounted in said jaw casting and on said threaded portion of a top rod, a permanent stop, against which said trigger lever abuts when the brakes are set and the brake shoes are worn, and a spring within said lever to return it to normal position when the brakes are released.
